UNITED STATES PATENT OFFICE.

SOLOMON H. LOORYE, OF WASHINGTON, DISTRICT OF COLUMBIA.

SUSPENDERS.

No. 845,801.

Specification of Letters Patent.

Patented March 5, 1907.

Application filed May 14, 1906. Serial No. 316,819.

To all whom it may concern:

Be it known that I, SOLOMON H. LOORYE, a citizen of the United States of America, residing at Washington, in the District of Columbia, have invented certain new and useful Improvements in Suspenders, of which the following is a description, reference being had to the accompanying drawing, and to the letters and figures of reference marked thereon.

This invention relates to suspenders of that general class in which evener-cords are employed between the shoulder-straps and rear buttonholes.

15 The principal object of the invention is to provide an improved means for guiding the evener-cord and permit greater freedom of movement with less wear.

A still further object of the invention is to 20 provide an improved attaching means between the evener-cord and the shoulder-straps.

A still further object of the invention is to 25 provide a continuous evener-cord slidable throughout its entire length.

With these and other objects in view the invention consists in the combination and arrangement of parts, as hereinafter set forth, and pointed out in the claims.

30 In the accompanying drawings, Figure 1 is a view of a pair of suspenders made in accordance with the invention. Fig. 2 is a detail view of one of the loop-carrying bars of the back-strap and one of the pivoted eyes detached, and Fig. 3 is a detail view of one of the shoulder-strap-connecting bars detached.

The shoulder-straps 10 are recessed or cut away at their rear ends and turned to form two spaced loops 11, which are arranged to

40 receive the opposite ends of a cross-bar 12, having hooked or turned ends 13 to prevent accidental detaching of the loops. The central portion of the bar carries a metal clip 14, to which is pivoted an eye 15. This eye has 45 an arcuate slot 16 for the passage of a loop 17, formed of leather or other suitable material and through which the evener-cord 18 passes.

The evener-cord 18, which is continuous, 50 carries similar loops 17 at its lower end, and these pass through slots formed in metallic eyes which are carried by the button-tabs 19.

The back strap or web 20 is provided with 55 links 21 at its upper and lower ends, and to these links are connected metal plates or bars 22, each of which is so shaped as to form a cen-

tral pivot lug or ear 23 and end lugs or ears 24. To the central ears of the upper and lower plates are pivoted eyes 26, having arcuate slots 27 struck from the pivotal centers 60 of the lugs. These slots receive loops 28, formed of leather or other suitable material and arranged to receive the evener-cord 18.

The outer ears 24 carry studs or pins 30, on which are pivoted eye members 31, each of 65 which has a curved slot 32 arranged on a line eccentric to the axis of its pin 30, and these slots receive loops 33, formed of leather or other suitable material and arranged for the passage of the evener-cord. 70

In suspenders of this general class it is found that where the side eyes or loops of the back-strap are formed of single-piece loops that the range of movement is limited, and if the wearer is engaged in manual labor or 75

physical exercise which requires considerable play of the back and shoulders there is undue friction on the evener-cord. In the present case each of the side loops is formed of two sections—the loop proper and the eye—and 80

owing to the eccentric connection of these two with respect to the pivot-point of the eye the evener-cord-guiding passage of the loop is free to move to almost any angular position with respect to the back-strap, and 85

thus automatically compensate for excess movement in any direction and form a guide that will offer a minimum of frictional resistance to the sliding movement of the evener-cord. The evener-cord, moreover, is 90 continuous and is slidable throughout its entire length through the entire series of loops, thus permitting free movement of the shoulders without excessive strain on any part of the suspenders. 95

The eyes are formed of single pieces of stamped sheet metal, which, with their curved slots and pivot-receiving openings, may be cheaply made at a single operation.

Having thus described my invention, what 100 I claim as new, and desire to secure by Letters Patent, is—

1. In suspenders of the type described, shoulder-straps, evener-cord loops connected thereto, rear button-tabs, evener-cord loops 105 carried thereby, a back-strap also having evener-cord loops, and an endless evener-cord passing through all of said loops and slidable throughout its entire length.

2. In suspenders of the type described, a 110 back-strap, an evener-cord, a bar or plate carried by the back-strap, eyes pivoted to

said bar or plate and having slots eccentric to their centers of movement, and evener-cord loops extending through said slots.

3. In suspenders, a shoulder-strap having recessed ends arranged to form two spaced end loops, a bar extending therethrough, and having turned or hooked ends, and a loop connection carried by the bar at a point between said end loops, and retained by said loops in a central position.

4. In suspenders of the type described, a single-piece stamped-metal eye having a pivot-receiving opening, a cord-receiving loop and a curved loop-receiving slot.

In testimony whereof I affix my signature 15 in presence of two witnesses.

S. H. LOORYE.
